Inventor
Raphael Randolph

UNITED STATES PATENT OFFICE

145,953

DESIGN FOR A COMBINATION ARBOR AND BOOKEND

Raphael Randolph, La Grange, Tex.

Application July 20, 1945, Serial No. 120,837

Term of patent 7 years

(Cl. D33—1)

To all whom it may concern:

Be it known that I, Raphael Randolph, a citizen of the United States, residing at La Grange, in the county of Fayette and State of Texas, have invented a new, original, and ornamental Design for a Combination Arbor and Bookend, of which the following is a specification, reference being had to the accompanying drawing, forming part thereof.

Fig. 1 is a front perspective view of a combination arbor and bookend showing my new design;
Fig. 2 is a rear perspective view thereof.

I claim:

The ornamental design for a combination arbor and bookend, substantially as shown.

RAPHAEL RANDOLPH.
